OPEN HEARTH FURNACE PORT
CONSTRUCTIONGeorge E. Rose and Joseph H. Dillon, Chicago,
Ill.

Application March 16, 1933. Serial No. 661,001

10 Claims. (Cl. 263—15)

This invention relates to an open hearth furnace construction. More particularly it relates to sealing means for a movable port as used in open hearth furnaces.

As is well known in the art, open hearth and similar metallurgical furnaces are double ended and are periodically reversed in their operation. Each end of the furnace thus serves alternately to introduce air and fuel and to carry off the products of combustion. The products of combustion are much higher in temperature than the incoming air and fuel and greatly exceed the air and fuel in volume.

In order to provide a construction in which sufficient velocity is given the incoming air and fuel and in which an outlet for the outgoing products of combustion is provided which will not be destroyed by high velocities and temperatures, movable restricting means have been provided, associated with the ends of the furnace. It is in a furnace with a movable hood or port for this purpose, as shown in the U. S. Patent No. 1,769,367, July 1, 1930, that the present invention is to be utilized. Due to the necessity for using brick work it is necessary to provide a relatively large clearance space between the movable port and the opening in the end wall of the furnace through which it is moved. Such a space permits the escape of gases from the furnace which in any condition is undesirable and under certain conditions is very destructive to the furnace.

The principal object of the present invention is to provide sealing means for the movable port.

A more specific object is to provide sealing means simultaneously operable with the port moving means for sealing the port in either of its extreme positions.

In the drawing we have illustrated an embodiment of the invention, in which:

Figure 1 is a fragmentary longitudinal section, showing one port end of an open hearth furnace with the invention applied thereto. The port is shown within the furnace in full lines, and withdrawn therefrom in dotted lines.

Figure 2 is an end elevation partly in section, as shown by the line 2—2 of Figure 1; and

Figure 3 is a portion of the same section shown in Figure 1, with the movable port in an intermediate position.

Referring to the drawing, a portion 6 of the roof of the furnace is shown, and also a portion 7 which forms the lower part of the furnace and the hearth of the melting chamber. A portion of an end wall 8 is also shown and the

upper end of a gas uptake 9 can be seen in Figure 1. As all of this construction is conventional, as shown in the patent above referred to, only such portions of the construction have been shown as are necessary to illustrate the present invention. 60

An opening 10, substantially semi-circular in cross section, is formed in the end wall 8. An arched supporting member 11 surrounds the interior of the circular portion of the opening. Said member is shown as being hollow for water cooling. A guideway 12, arranged at a slight angle downwardly, extends through the end wall 8 of the furnace and forms a support for a hood member or movable port 13, as such members are commonly called. The guideway or plate 12 is formed as a hollow plate for water cooling. It extends rearwardly from the end wall of the furnace a distance beyond the extreme outward position of the movable port 13 and inwardly beyond the extreme inner end position of said port. An opening 14 is formed in the plate 12 in registration with the uptake 9. The forward end of the port is slightly restricted to form means for directing the gases into the furnace. 70

It will be noted that there is a considerable clearance space between the outside wall of the port 13 and the arched member 11 which forms a liner for the opening 10 in the end wall of the furnace. This clearance space is necessary as structures of this type cannot be built within small dimensions and as the distortion due to the high temperatures is apt to cause relative changes in the dimensions of the different structures. 85

Outside the end wall of the furnace a supporting structure 15 is provided. Said structure, as illustrated, is formed of vertical beams which may be supported and braced by any suitable means. A horizontal transverse rock shaft 16 is supported in bearings 17 mounted on the beams of the supporting structure. A lever 18 is rigidly secured to the rock shaft 16. Said lever may be operated by any properly controlled source of power. 90

A sleeve 19, rigidly secured to the shaft 16, supports, rigidly connected thereto, a pair of downwardly extending lever arms 20. Said arms are pivotally connected at their lower ends to links 21 which are in turn pivotally connected to the port 13. 95

On a pair of brackets 22, which are secured to the vertical beams of the supporting structure 15, a transverse shaft 23 is mounted. Intermediate the ends of said shaft a pair of lift- 105

ing levers 24 are pivoted intermediate their ends. At the forward ends of said levers extensions 25 are adjustably secured. Said extensions project into a recess 26 formed in the end wall of the furnace. Flexible cables 27 connect the ends of said extensions to a sealing member 28. Said sealing member is arcuate in form and is fitted to the outside of the port 13, terminating adjacent the plate 12 at each side of the port. The member is of a thickness sufficient to maintain it in shape and is of a width sufficient to overlap the outer edge of the member 11, whereby it forms a seal of the clearance space between the port and the lining member 11.

15 The lifting levers 24 are provided at their outer ends with small rollers 29 which serve as cam followers, being positioned to engage cams 30 secured to the arms 20, which form the means for moving the port.

20 The cams 30 are particularly shaped to obtain a desired control of the position of the sealing member 28. As shown in Figure 1, the port 13 is in its extreme operative position within the furnace and the sealing member 28 is in the clearance covering position. It will be noted that the cam rollers 29 are at one side of the cams 30. At the initial movement of the rock shaft 16 to move the port into its extreme outward position, as shown in dotted lines in Figure 1, the lifting levers 24 are given an appreciable angular movement during a very slight angular movement of the rock shaft 16. This is due to the rapidly increasing radius of the cam surface, which is evident from an inspection of Figure 1. During this initial movement the sealing member 28 is lifted out of contact with the movable port, whereby it will not be engaged or injured in any way by the rough brick surface of the port.

40 Substantially all of the central portion of each of the cams 30 is of a uniform radius with respect to the axis of the shaft 16, whereby no movement of the sealing member is brought about during the intermediate movement of the port, said sealing member being held in a free non-engaging position. During the final movement of the port as it approaches its extreme outward position, the cam followers 29 run over the edge of the cams 30 and lower the sealing member 28 into contacting position with the port. The lifting levers 24 and the sealing member are again in their initial position. This feature of the construction is clearly shown by the dotted line position in Figure 1. Figure 3 shows the position of the sealing member during the movement of the port. By providing the rapid lift at the beginning of the port and the rapid lowering at the end of the movement, the sealing member 28 is not injured or dragged from sealing position by movement of the port after engagement of the sealing member therewith or before the sealing member is lifted.

65 The operation of the improved port construction and the sealing means therefor, has been explained in connection with the description of the elements making up the construction.

70 It is to be understood that applicants have shown only a preferred construction and that they claim as their invention all modifications falling within the scope of the appended claims.

75 What is claimed is:

1. In an open hearth furnace having an opening formed in a wall thereof and a movable port slideable through said opening in clearance relation with respect thereto, means for moving

said port into a position within the furnace and into a position withdrawn from the furnace, a sealing member shaped to fit around the port and to engage the wall therearound for sealing the clearance space between the port and the opening formed in the wall, and means for lifting said member out of contact with the port during movement of the port.

2. In an open hearth furnace having an opening formed in a wall thereof and a movable port slideable through said opening in clearance relation with respect thereto, means for moving said port into a position within the furnace and into a position withdrawn from the furnace, a sealing member shaped to fit around the port and to engage the wall therearound for sealing the clearance space between the port and the opening formed in the wall, and means for lifting said member out of contact with the port during movement of the port, the means for moving the sealing member being interconnected with the means for moving the port.

3. In an open hearth furnace having an opening formed in a wall thereof and a movable port slideable through said opening in clearance relation with respect thereto, means for moving said port into a position within the furnace and into a position withdrawn from the furnace, a sealing member shaped to fit around the port and to engage the wall therearound for sealing the clearance space between the port and the opening formed in the wall, and means for lifting said member out of contact with the port during movement of the port, the means for moving the sealing member being interconnected with the means for moving the port and operable to hold the sealing member out of contact with the port during the entire range of movement of the port and to seat said member against the port and the furnace wall in the two extreme positions of the port with respect to the wall of the furnace.

4. In an open hearth furnace having an opening formed in a wall thereof and a movable port slideable through said opening in clearance relation with respect thereto, means for moving said port into a position within the furnace and into a position withdrawn from the furnace, a sealing member shaped to fit around the port for sealing the clearance space between the port and the opening formed in the wall, means for lifting said member out of contact with the port during movement of the port, and connecting means between the port moving means and said lifting means operable to actuate the lifting means upon initial movement of the port from either of its positions.

5. In an open hearth furnace having an opening formed in a wall thereof and a movable port slideable through said opening in clearance relation with respect thereto, means for moving said port into a position within the furnace and into a position withdrawn from the furnace, a sealing member shaped to fit around the port for sealing the clearance space between the port and the opening formed in the wall, means for lifting said member out of contact with the port during movement of the port, and connecting means between the port moving means and said lifting means operable to actuate the lifting means to lower the sealing member into sealing position at the end of a movement of the port into either of its positions.

6. An open hearth furnace having an end wall formed with an opening therethrough and a

5	means for reciprocating the port mounted on said structure, a cam actuated by said means, a sealing member positioned to close the clearance space between the port and the opening in the end wall, lifting means mounted on the frame structure, means for connecting said means to the sealing member, and cam following means on the lifting means positioned to engage the cam whereby the position of the sealing member is determined by movement of the port actuating arm.	80
10	7. An open hearth furnace having an end wall formed with an opening therethrough and a movable port mounted for reciprocation in said opening with clearance relation with respect to the end wall and in combination therewith, a supporting structure adjacent the furnace, means for reciprocating the port mounted on said structure, a cam actuated by said means, a sealing member positioned to close the clearance space between the port and the opening in the end wall, a lifting lever pivoted on the frame structure, means for connecting one end of said lifting lever to the sealing member, and cam following means at the other end of the lifting lever positioned to engage the cam on the actuating lever whereby the position of the sealing member is determined by movement of the port actuating arm.	85
15	8. An open hearth furnace having an end wall formed with an opening therethrough and a movable port mounted for reciprocation in said opening with clearance relation with respect to the end wall and in combination therewith, a supporting structure adjacent the furnace, a horizontal shaft mounted on said supporting structure, an actuating arm rigidly connected to said shaft, an actuating link connecting said shaft and the movable port, a cam mounted on said arm, a sealing member positioned to close the clearance space between the port and the opening in the end wall, lifting means mounted on the frame structure, means for connecting said means to the sealing member, and cam following means on the lifting means positioned to engage the cam whereby the position of the sealing member is determined by movement of the port actuating arm.	90
20	9. An open hearth furnace having an end wall formed with an opening therethrough and a movable port mounted for reciprocation in said opening with clearance relation with respect to the end wall and in combination therewith, a supporting structure adjacent the furnace, a horizontal shaft mounted on said supporting structure, an actuating arm rigidly connected to said shaft, an actuating link connecting said shaft and the movable port, a cam mounted on said arm, a sealing member positioned to close the clearance space between the port and the opening in the end wall, a lifting lever pivoted on the frame structure, means for connecting one end of said lifting lever to the sealing member, and cam following means at the other end of the lifting lever positioned to engage the cam on the actuating lever whereby the position of the sealing member is determined by movement of the port actuating arm.	95
25	10. An open hearth furnace having an end wall formed with an opening therethrough and a movable port mounted for reciprocation in said opening with clearance relation with respect to the end wall and in combination therewith, a supporting structure adjacent the furnace, a horizontal shaft mounted on said supporting structure, an actuating arm rigidly connected to said shaft, an actuating link connecting said shaft and the movable port, a cam mounted on said arm, a sealing member positioned to close the clearance space between the port and the opening in the end wall, a lifting lever pivoted on the frame structure, means for connecting one end of said lifting lever to the sealing member, and cam following means at the other end of the lifting lever positioned to engage the cam on the actuating lever whereby the position of the sealing member is determined by movement of the port actuating arm.	100
